[57] CLAIM

The ornamental design for a hot water heater shut off valve,
as shown and described.

DESCRIPTION

FIG. 1 is a front, top and side perspective view of the hot
water heater shut off valve showing my new design;
FIG. 2 is a front elevational view thereof, the rear being a
mirror image;

FIG. 3 is a left hand side elevational view thereof;

FIG. 4 is a right hand side elevational view thereof;

FIG. 5 is a top plan view thereof; and,

FIG. 6 is a bottom plan view thereof.

The cords are shown broken away to indicate indeterminate
length.
